(57) **CLAIM**

The ornamental design of a fish finder protective case as shown and described.

DESCRIPTION

FIG. 1 is a top perspective view of an embodiment of a fish finder protective case;

FIG. 2 is a front side view of the fish finder protective case of FIG. 1;

FIG. 3 is a back side view of the fish finder protective case of FIG. 1;

FIG. 4 is a left side view of the fish finder protective case of FIG. 1;

FIG. 5 is a right side view of the fish finder protective case of FIG. 1;

FIG. 6 is a top side view of the fish finder protective case of FIG. 1; and,

FIG. 7 is a bottom side view of the fish finder protective case of FIG. 1.

The portions illustrated in broken lines on the figures, if any, are for illustrative purposes only and form no part of the claimed design. The dot-dash broken line(s) define the bounds of the claimed design and form no part thereof.
